 corporation of New York

Application December 15, 1945, Serial No. 635,384

6 Claims. (Cl. 210—156)

1

This invention relates to a stopper and has particular reference to a stopper for the intake pipe of a dairy water heater or the like such as that disclosed and claimed in the application of Ernst Koppel, filed December 8, 1944, Serial No. 567,252, now Patent Number 2,448,183.

In the operation of a dairy water heater such as that disclosed in the application referred to a pail of cold water is poured into the container at the top of the heater and a pail of hot water is drawn off from the outlet pipe at one side of the heater. Since a heater of this type is often located where flies and filth may accumulate in the open container of the heater, it is desirable to close the pipe leading from the container to the heater proper when the heater is not in use. At the same time the closure member must be of such a nature that it can be moved to a position at which cold water placed in the container will flow into the pipe leading to the heater tank.

When water flows into the pipe leading from the container it is desirable that flies and filth be filtered out. The stopper unit should also be of a type that need not be removed since it might be misplaced and readily lost.

One object of the invention is to provide a stopper unit that operates as a closure member for a pipe opening and also as a filter when fluid flows into the pipe.

Another object is to provide an efficient stopper unit at low cost to control the flow of water in a dairy water heater.

Another object is to provide a stopper unit that need not be completely removed to flow fluid into the pipe in which it is located.

A further object is to provide a stopper unit that will not be readily lost or misplaced.

Another object is to provide a stopper unit for the container of a dairy water heater that permits use of the same pail for filling the heater with cold water and to draw off hot water.

These and other objects of the invention will appear hereinafter in connection with the following description of the embodiment of the invention illustrated in the accompanying drawing.

In the drawing:

Figure 1 is a longitudinal sectional view of a portion of a dairy water heater partly in elevation with the stopper unit closing the pipe leading to the container at the top of the heater;

Fig. 2 is a section taken on line 2—2 of Figure 1;

Fig. 3 is a similar section showing the position of the nipple and slot when the stopper unit is being assembled in the inlet pipe;

2

Fig. 4 is an enlarged view of a portion of a dairy water heater and showing the stopper unit in its uppermost position to permit flow of water into the pipe leading from the container; and

Fig. 5 is a fragmentary top plan view showing how the splash guard prevents registry of the nipple and slot after assembly.

The drawings illustrate a dairy water heater 1 having an outlet 2 extending through the casing at the upper right side of the heater, and inlet pipe 3 leading to the heater proper from a receptacle 4 located at the top of the heater and a stopper unit 5 disposed to close off the inlet to pipe 3.

The upper portion of receptacle 4 has a flange 6 that extends around the inner periphery of the receptacle and supports the removable splash ring 7.

The receptacle 4 may be assembled with the inlet pipe 3 in a number of different ways. For example in the drawing illustrating the invention the opening in the receptacle leading to pipe 3 is surrounded by a flange 8. The flange is aligned with inlet pipe 3 and rests within a fitting 9 which is threaded onto the upper end of pipe 3. A gasket 10 is disposed between the upper end portion of fitting 9 and flange 8 to insure there will be no leakage at the joint therebetween.

The lower end portion of flange 8 is provided with the inwardly turned lip 11, the use of which will be more fully described hereinafter.

The stopper unit 5 operates as a closure member to close off pipe 3 from receptacle 4 when it is not desired to draw water from the heater and as a filter member when water is flowed into the pipe 3 from receptacle 4 as illustrated in Fig. 4 in order to draw off water from outlet pipe 2 of the heater.

The stopper unit 5 comprises a stopper 12, a hollow perforated cylinder or screen 13 and a gasket 14.

The stopper 12 is preferably of conical shape to permit wedging of the same into the upper end of pipe 3 when it is desired to close off the latter. The stopper preferably is of rubber or other material that may be readily molded and which will withstand corrosion in service.

The cylinder 13 is of sheet metal and has perforations 15 therein to permit flow of water therethrough when cold water is poured into receptacle 4 to force hot water from the heater through outlet pipe 2. The cylinder 13 may also be of other construction such as screening secured to metal end frames to give rigidity thereto.

The upper end of cylinder 13 is molded into the lower portion of the conical stopper 12 to become an integral part thereof and rigidly support the same.

The gasket 14 is suitably secured to the lower end of sheet metal cylinder 13, and has a diameter with relation to the diameter of pipe 3 to provide a press fit therebetween. The fit between gasket 14 and pipe 3 is of such a nature that the gasket 14 will hold the stopper unit 5 rigidly in place at whatever position the unit is located within the upper end of pipe 3.

The gasket 14 may be of rubber or other suitable composition that will withstand corrosion in service, and which is compressible to obtain the tight fit with pipe 3 that is desired. Gasket 14 is provided with a vertical slot 16 which registers with lip 11 of flange 8 when the stopper unit 5 is initially assembled within the heater.

A handle 17 is molded into the upper end of cork 12 and extends upwardly above the top of container 4 so that it may be readily grasped by the operator. The upper end portion of the handle 17 is flanged away from ring 7 and has a hand ring 18 to additionally provide the same for ready manipulation.

The operator of the dairy heater may grasp the handle 17 and force the same downwardly to locate the stopper 12 in the flanged opening of receptacle 4 leading to pipe 3 to close off pipe 3 from receptacle 4 when water is not being drawn from the heater.

When it is desired to draw off hot water from the heater, cold water is poured into container 4 and the operator then grasps ring 18 of handle 17 and pulls the same upwardly a slight distance. This removes stopper 12 from the opening of flange 8 leading to pipe 3 and exposes the filter 13. Cold water then flows into pipe 3 from receptacle 4 through the sheet metal cylindrical filter 13. The gasket 14 remains in the upper end of pipe 3 and holds the stopper unit 5 in the position desired by the operator.

The stopper unit 5 is assembled within the flange 8 of the receptacle and inlet pipe 3 before splash ring 7 is placed in position on flange 6 of the receptacle.

In assembling the stopper unit in place, the slot 16 in gasket 14 is registered with lip 11 of flange 8 as shown in Fig. 3 and the stopper unit is pushed downwardly until gasket 14 passes beyond lip 11. The stopper 5 is then turned to a position where slot 16 no longer registers with lip 11 as shown in Fig. 2.

When turned to final position, the handle 17 is at a position as shown in Fig. 4 at which splash ring 7 can be placed on flange 6 of receptacle 4. When the ring is in place it is impossible to turn handle 17 to a position where slot 16 and lip 11 register as particularly illustrated in Fig. 5. Thus after assembly, the stopper unit 5 may be moved up and down at will by the operator, but cannot be removed from the opening in the receptacle leading to inlet pipe 3 as removal is prevented by lip 11.

Other means to prevent removal of the stopper unit 5 in service than that illustrated and described may well be employed.

The filter cylinder 13 prevents foreign matter such as flies, filth or the like from following the water from receptacle 4 into pipe 3 and thus the hot water drawn off from outlet pipe 2 is clean and generally free of filth that would ordinarily be present if the stopper unit of the invention were not employed.

By providing a stopper unit, as described, filth is prevented from getting into the water of the heater and it is not necessary to completely remove the stopper from the heater to permit water to flow into the heater. There is no danger that the stopper unit will be lost or misplaced as would be the case were it necessary to remove the same. Also the stopper unit cannot be completely removed from the heater unless splash ring 7 is removed and slot 16 registered with lip 11 by turning the stopper unit.

It is possible to construct the stopper unit in other ways than that described to carry out the purposes of the invention but the embodiment shown and described is very effective and readily produced at low cost.

Various embodiments of the invention may be employed within the scope of the accompanying claims.

20 I claim:

1. A stopper unit for the intake pipe of a dairy water heater or the like in which said pipe leads from a container receiving the water flowed into the heater and an outlet pipe leads from the heater to supply hot water in relation to the input of cold water through the intake pipe, said stopper unit comprising a stopper adapted to close said intake pipe to prevent water flowing thereto from said container, a filter member secured to the lower end of said stopper and disposed to filter out foreign matter when the stopper is raised from the intake pipe and water flows through said filter member to the intake pipe from said container, and means to hold the stopper unit rigidly in place in said intake pipe at whatever position the unit is located within the upper end of the intake pipe to regulate the flow of water from the container to the intake pipe and the consequent output of water by the heater.

2. A stopper unit for the intake pipe of a dairy water heater or the like in which said pipe leads from a container receiving the water to carry the water into the tank of the heater, said stopper

45 unit comprising a stopper adapted to close the inlet of said pipe to prevent water flowing thereto from said container, a filter ring of rigid construction secured to the lower end of said stopper and disposed in the path of the flow of water from the container to the intake pipe to filter out foreign matter from the water when the stopper is raised from the intake pipe and water flows to the pipe from said container, and a gasket secured to the lower end of the filter ring and 50 radially compressed within the upper end of the intake pipe to retain the filter portion of the stopper unit therein at defined positions when the stopper is raised from the pipe.

3. A stopper unit for the intake pipe of a dairy water heater or the like in which said pipe leads from a container receiving the water to carry the water into the tank of the heater, said stopper unit comprising a conical shaped stopper disposed to close the inlet of the intake pipe to prevent water flowing thereto from said container, a perforated sheet metal cylinder molded into the lower end of the stopper and disposed at the inlet to said intake pipe in the path of the flow of water from the container to the pipe to filter out foreign matter from the water when the stopper is raised and water flows to the intake pipe from said container, and a gasket secured to the lower end of said cylinder and radially compressed within the upper end of the intake pipe to retain the filter in the pipe at a

55 60 65 70 75

defined position when the stopper is raised from the pipe and seal the cylinder against passage of water between it and the pipe.

4. A stopper unit for the intake pipe of a dairy water heater or the like in which said pipe leads from a container receiving the water to carry the water into the tank of the heater, said stopper unit comprising a conical shaped stopper disposed to close the inlet of said intake pipe to prevent water flowing thereto from said container, a perforated sheet metal cylinder molded into the lower end of the stopper and disposed at the inlet to said intake pipe in the path of the flow of water from the container to the pipe to filter out foreign matter from the water when the stopper is raised and water flows to the intake pipe from said container, a gasket secured to the lower end of said cylinder and radially compressed within the upper end of the intake pipe to retain the filter in the pipe when the stopper is raised from the pipe and seal the cylinder against passage of water between it and the pipe, and a handle molded into the upper end of said stopper to permit ready manipulation of the stopper unit to wedge the stopper into the intake pipe for closing the same and to raise the stopper and permit water to flow to the pipe from the container through said perforated filter cylinder.

5. A stopper unit for the intake pipe of a dairy water heater or the like in which said pipe leads from a container receiving the water to carry the water into the heater with said container having a flange surrounding the opening in the container leading to said pipe and provided with an inwardly turned lip, said stopper unit comprising a stopper adapted to close the inlet of the intake pipe to prevent water flowing thereto from said container, a filter member secured to the lower end of said stopper in the path of the flow of water from the container to the pipe and disposed to filter out foreign matter from the water when the stopper is raised from the intake pipe and water flows to the pipe from said container, a gasket secured to the lower end of

the filter ring and radially compressed within the upper end of the intake pipe, and a vertical slot extending through said gasket and disposed to register with the lip on the flange of the container when the stopper unit is assembled with the heater and to be out of registry with the lip when the stopper unit is turned in service to prevent removal of said stopper unit.

6. In a dairy water heater having a stopper unit to regulate the flow of water from a water receiving container through a flanged opening therein to the inlet pipe of the container, said stopper unit comprising a central filter member secured at one end to a stopper and at the other end to a gasket disposed in the inlet pipe and located in the path of the flow of water from the container to the pipe when the stopper is raised from the pipe, and means to prevent removal of said stopper unit which comprises an inwardly turned lip on the flange of the container disposed to register with a slot extending vertically through said gasket when the stopper unit is assembled with the heater and with said slot out of registry with the lip when the stopper unit is turned in service to prevent removal of said stopper unit, a splash guard supported on the upper end of the container, and a handle secured to the stopper of the unit and extending upwardly to a line above said splash guard, said splash guard, preventing turning of said handle when in place on the container to prevent the lip and slot from registering and removal of the stopper unit when the heater is in service.
